AIRPORT CONTROL AND SIGNALING
SYSTEM

Laurence J. Lesh, Chicago, Ill., assignor, by mesne assignments, to Associated Electric Laboratories, Inc., Chicago, Ill., a corporation of Delaware

Application July 5, 1929, Serial No. 376,032

4 Claims. (Cl. 177—352)

The present invention relates in general to airport control and signaling systems. The main object of the invention is the provision of an automatic airport lighting control and fog alarm system.

According to one feature of the invention, the hangar lights and the correct floodlight for landing, governed by wind direction, may be controlled by the pilot of an airplane approaching the landing field.

Another feature of the invention lies in the provision of receiving and recording apparatus at the terminal airports of the route whereby such terminal stations are notified of the landing of a plane and the particular field at which the plane is landing.

According to another feature of the invention, the presence of fog at a particular field will operate indicators at the two adjacent fields to warn pilots approaching from either direction of this fog condition.

Still another feature lies in the provision of selective receiving apparatus at the terminal stations which is arranged to operate recording devices to make a permanent record of the fog conditions at each field and the time such conditions prevailed.

Numerous other features of the invention will become apparent from the following specification when read in connection with the accompanying drawings, comprising Figs. 1 to 3, inclusive. These figures show by means of the usual schematic diagram, an air route consisting of two terminal stations and four intermediate flying fields.

Fig. 1 shows in detail the apparatus and circuit arrangement of the equipment located at terminal station No. 1. The recorder or register CR may be any of the well known types in which the recording tape is wound on reels which are rotated only during the time that signals are being received. The recorders or registers FR1 and FR2 are of the type with a continuously rotating cylinder making one revolution in twenty-four hours and on which signals are recorded according to the time at which they are received. Fig. 1 also shows two intermediate flying fields F1 and F2 which have been indicated by dotted rectangles. The equipment at each of these fields is the same as is shown in detail for flying field F3.

Fig. 2 and the left-hand portion of Fig. 3 show in detail the apparatus and the circuit arrangement of the equipment located at flying field F3. The apparatus RT within the dotted

rectangle in the upper left-hand corner of Fig. 2 indicates a radio transmitter such as is located in each of the planes operating over the route. Each of these radio transmitters is equipped with an impulse sender suitable for sending impulses at a predetermined frequency. In the drawings, a Vibroplex key has been illustrated for this purpose. When the key is operated to close contacts 160 the weighted portion is caused to vibrate at its natural period of vibration and closes contacts 160 at each vibration, thereby transmitting a series of dot impulses at a definite frequency. The frequency of these impulses may be adjusted by varying the position of the weight 161 on the lever of the key. Dash impulses may be transmitted by operating the key so as to close contacts 151. These contacts are mounted sufficiently near the pivot point of the key that the vibrations of the key lever do not open these contacts and a continuous dash will be sent out as long as the key is held in this position.

The rotary switch CS may be of the rotary lineswitch type well known in the art of automatic telephony. The switch comprises two rows of stationary bank contacts which are wiped over by the wipers 92 and 93. These wipers are mounted on a shaft which is rotated under control of the rotary magnet 89. The oscillator shown at O, Fig. 3, is of the type disclosed and described in my co-pending application Serial No. 353,283, filed April 8, 1929. The arrangement of the lights and fog indicators at the flying field is shown within the dotted rectangle in the left-hand portion of Fig. 3. The lights L1 to L4, inclusive, are the floodlights used in landing. N1 and N2 are arrow-shaped neon lamp indicators which are used to warn pilots of fog conditions at flying fields F2 and F4, respectively. PH is a photo-electric cell and may be any one of a number of well known types.

In the right hand portion of Fig. 3 are indicated the fourth intermediate flying field F4 and terminal station #2. The equipment and circuit arrangement at field F4 is similar to that shown in detail for F3 while the apparatus at terminal station #2 is similar to that shown in detail for terminal station #1.

The operation of the system will now be explained in detail in connection with the equipment illustrated in the drawings for flying field F3 and terminal station #1. It will be first assumed that a plane is approaching the flying field F3 and wishes to land. As he nears the field, the pilot will operate the Vibroplex key 43, associated with the radio transmitter RT, Fig. 2,

located in the plane, so as to close contacts 160. The Vibroplex key vibrates at a definite predetermined frequency, closing contacts 160 at each vibration, and causes a series of impulses to be transmitted to the airplane antenna 46. This series of impulses is received at the flying field radio receiving set RR through its antenna 47. As the receiving set RR may be any one of a number of well known makes, the detailed operation will not be explained. It is thought sufficient to state that each impulse received by the receiving set RR is amplified by the tube 48 and operates the plate relay P. Thus the plate relay P will be energized and deenergized in synchronism with the vibrations of the Vibroplex key 43. Each time that relay P operates it closes obvious circuits for relays 51, 53, 64, and 71.

It might be well to explain at this time that each company which operates planes over the route including field F3 may be assigned a different Vibroplex key frequency. If this is done, all the planes of one company will be equipped with Vibroplex keys of the same frequency. A corresponding tuned relay, such as 53 or 64, is provided for each frequency in use. A separate hangar, such as H1 or H2 of Fig. 3, is also provided for each company operating planes over the route.

Continuing with the explanation of the system, it will be assumed that the plane which is preparing to land is owned by Company A whose Vibroplex frequency is f_1 . It will further be assumed that hangar H1 is owned by Company A. As described above, plate relay P will energize and deenergize at a frequency f_1 in response to the operation of the Vibroplex key 43. Relays 51 and 71 are operated each time the contacts 50 are closed. The function of these relays will be explained later. The circuits of all tuned relays, such as 53 and 64, are also closed at each impulse and these relays tend to attract their weighted armatures, such as 54 and 65, respectively. Each of these weighted armatures is tuned to vibrate at a frequency equal to the Vibroplex frequency assigned to the plane of one of the companies. It will be assumed that armature 54 of relay 53 is tuned to respond to frequency f_1 .

The energization of relay 53 causes the weighted armature 54 to vibrate at its natural frequency and, when the vibrations reach a certain amplitude, the armature operates the contacts 55. The closing of these contacts completes a circuit from ground, contacts 55, back contacts 59, winding of relay 56, normally closed contacts of the release key 76, back contacts 80 of relay 79, winding of relay 81, to battery. Relay 56 and relay 81 operate in this circuit. At contacts 58, relay 56 closes a locking circuit extending from ground, contacts 58, winding of relay 60, winding of relay 57, winding of relay 56, normally closed contacts of the release key 76, back contacts 80, winding of relay 81, to battery. Relays 60 and 57 are energized in this circuit and are locked up in series with relays 56 and 81. At contacts 59, relay 56 opens its initial energizing circuit to prevent the shunting of relays 57 and 60 should the tuned relay 53 be again operated by another plane belonging to Company A. The result of the operation of relay 81 and the reason for its "slow to operate" feature will be explained later.

At contacts 61, relay 60 closes a circuit for the floodlight control relay 108, Fig. 3, which extends from ground, contacts 61, conductor 101, winding 75 of relay 108, to battery. Relay 108 operates and

at contacts 107 connects one side of the power source to one terminal of each of the flood-lights and hangar lights in multiple by way of conductor 109. At contacts 62, relay 60 completes the circuit for the light at hangar H1. This circuit extends from one side of the power source, conductor 106, conductor 102, contacts 62, conductor 100, through the light at hangar H1, conductor 109, contacts 107, to the other side of the power source by way of conductor 105.

When relay 108 operated and closed contacts 107 as described above, a circuit was completed for the correct flood-light, determined by the wind direction, to be used by the pilot in landing. The lighting of the correct flood light is controlled by the wind vane V. In the particular case illustrated, it is assumed that the wind is from the north-west as indicated by the pointer 111 of the wind vane V. As is well known in aviation, a plane must be landed against the wind. It is, therefore, obvious that the flood-light L3 in the south-east corner of the flying field should be lighted so that the pilot will have the light at his back while landing. The above-mentioned circuit for the flood-light extends from one side of the power supply, conductor 106, conductor 110, pointer 111 of the wind vane V, stationary contact 112, conductor 113, through the flood-light L3, conductor 109, contacts 107, to the other side of the power supply by way of conductor 105. All lights required by the pilot for landing have now been turned on in response to the operation of the Vibroplex key 43 in the airplane radio transmitting set.

The manner in which the terminal stations are informed of the landing of a plane at a particular field will now be described. When relay P is operated in accordance with the Vibroplex frequency f_1 in response to the series of impulses received by the radio receiving set RR, it closes an obvious circuit for relay 71 at contacts 50 each time it operates. Accordingly, relay 71 energizes and deenergizes at the same rate as relay P. Each time relay 71 energizes and closes its contacts 78, a circuit is completed from ground, contacts 98 of relay 97, contacts 78; winding of relay 79, land line L, winding of relay at flying field F2, corresponding to relay 79, land line L extending to flying field F1, the relay at F1 corresponding to relay 79, land line extending to terminal station #1, normally closed contacts of key 1, winding of relay 2, to battery. A branch of this circuit extends over the land line L to flying field F4, relay at F4 corresponding to relay 79, land line L extending to terminal station #2, normally closed contacts of release key 114, winding of relay 115, to battery. Thus a series of impulses, occurring at a frequency governed by the frequency of the Vibroplex key in the airplane which is preparing to land, is transmitted over the land line to each of the terminal stations. The frequency at which these impulses occur indicates to the terminal stations the identity of the company whose plane is preparing to land, as will now be described.

Referring now to terminal station #1, illustrated in Fig. 1, relay 2 is operated in response to each impulse received over the land line. Each time it operates an energizing circuit is closed at contacts 3 for the tuned relays such as 4 and 8. One of these relays is provided for each frequency in use in the system. It will be assumed that the relay 4 is tuned, by means of its weighted armature 5, to respond to the frequency f_1 . Accordingly the closing of contacts 3 in accordance with this frequency and the subsequent impulses

of current to the relay 4, will cause the weighted armature 5 to vibrate at its natural frequency, which is equal to the frequency f_1 . When the vibrations reach a certain amplitude, the armature 5 closes contacts 6, thereby completing an obvious circuit for the signal lamp 7 and relay 152 in multiple. Relay 152 operates and at contacts 155 closes a locking circuit for itself extending from ground, normally closed contacts of the release key 159, contacts 155, winding of relay 152, to battery. A branch of this circuit extends through the lamp 7 to battery. The relay 152 is thereby maintained operated and lamp 7 is kept lighted after the series of identifying impulses has ceased and the relay 4 has opened contacts 6. At contacts 153, relay 152 closes an obvious circuit for the bell 154.

When the attendant at the terminal station hears the alarm bell, he knows that a plane is preparing to land at one of the flying fields. As the lamp 7 is individual to the tuned relay 4, the lighting of this lamp identifies the company whose plane is preparing to land. When the attendant has taken note of the fact that a plane is preparing to land and has identified the company to which the plane belongs, he may stop the bell and extinguish the lamp by depressing the release key 159. The opening of the contacts of this key opens the locking circuit of relay 152 and the circuit of lamp 7. Relay 152, in releasing, opens the circuit of the alarm bell at contacts 153.

In addition to ringing the bell 154 to attract the attention of the attendant and lighting the lamp 7 to indicate which plane is preparing to land, the series of identifying impulses is also recorded on the pen register CR. When relay 2 is operated in response to the receipt of the first impulse, it closes a circuit for the operating magnet 12 of the recorder CR and the slow-to-release relay 19 in multiple. Relay 19 operates and withdraws pawl 18 from the ratchet teeth on the reel 17. Reel 17 is then revolved by means of spring power and starts the tape 15 so that the incoming signals may be recorded. Relay 19 is made slow to release and remains operated during the series of impulses and for a short time afterwards to insure the recording of all signals before the tape 15 is stopped. Operating magnet 12 is energized at each impulse and attracts its armature 13, thereby forcing the pencil 14 into contact with the tape 15. Thus a permanent record is made of the series of identifying impulses and the identity of the plane that transmitted these impulses may be determined at any time by counting the number of dots recorded per unit distance of tape, thereby determining the frequency of the received signal.

Returning now to the point where relay 81 of Fig. 2 was operated in series with relay 56 and locked in series with relays 56, 60 and 57, the closing of contacts 82 completes an obvious circuit for the slow-to-operate relay 83. A multiple branch of this circuit extends from ground, contacts 82, back contacts 84 of relay 83, normal bank contact of the rotary switch CS, wiper 92, rotary interrupter springs 91, winding of rotary magnet 89, winding of relay 97, to battery. The rotary magnet 89 and relay 97 are energized in this circuit before relay 83 has had time to operate and open its contacts 84. The operation of relay 97 opens contacts 98, thereby removing ground from the armature spring of relay 11 and preventing any further sending of identifying impulses by the relay 11. This is done so that

the Vibroplex frequency impulses will not interfere with the sending of the field code.

It might be well at this time to explain the adjustments of the tuned relays and the slow acting feature of relay 81. When the identifying impulses are received at the flying field and cause the operation of one of the tuned relays, such as 53 and 64, these impulses are at the same time repeated to the terminal station to bring about the operation of one of the tuned relays, such as 10 4 and 8. As explained above, the operation of the tuned relay 53 brings about the energization of relay 81 and, in turn, the operation of relay 97. Relay 97, at contacts 98, opens the impulsive circuit of relay 11. It will therefore be seen that 15 the tuned relay at the terminal station must operate and cause the operation of the locking relay, such as 152, before relay 97 operates and opens the impulsive circuit. The tuned relays at the flying field are therefore adjusted so that 20 their contacts are a relatively large distance away from the weighted armatures and will not be closed until the armatures are vibrating at nearly maximum amplitude. It is obvious that a relatively large number of impulses and a correspondingly long interval of time will then be required to operate the contacts of these relays.

On the other hand, the tuned relays at the terminal stations are adjusted with the contacts relatively close to the weighted armature. Thus 30 a smaller number of impulses and a shorter interval of time are required to operate the contacts of these relays. In addition to the adjustments of the tuned relays, relay 81 is made slow to operate, thereby allowing a still greater interval of 35 time to elapse before relay 97 operates and opens the impulsive circuit to the terminal stations. The combined effect of the difference in adjustment of the tuned relays and the slow acting feature of relay 81 insures positive operation of 40 the tuned relay at the terminal station.

Returning now to the operation of the switch CS, when the rotary magnet 89 operated it opened contacts 91, thereby opening its energizing circuit and allowing it to deenergize and 45 advance the wipers one step. As soon as the wipers are advanced to the second bank contacts, a circuit is closed from ground at the bank contact, wiper 92, interrupter contacts 91, winding of rotary magnet 89, winding of relay 97, to 50 battery. The operation of the rotary magnet 89 again opens contacts 91 and allows the magnet to deenergize, thereby advancing the wipers another step. This action continues and the wipers of the rotary switch are advanced step by step. 55 Relay 97 is made slow-to-release so that it is maintained operated during the stepping of the rotary switch and until the switch has returned to normal.

When the wipers of the rotary switch are 60 moved into engagement with the fourth bank contact, a circuit is closed from ground, wiper 93, bank contact #4, winding of relay 95, to 65 battery. Relay 95 operates and closes its contacts 96, thereby sending a ground impulse to each of the two terminal stations. This circuit extends from ground, contacts 96, winding of relay 19, land line L extending to F2, winding of relay at F2 corresponding to relay 19, land line L extending to F1, winding of relay at F1 corresponding to relay 19, land line L extending to 70 terminal station #1, normally closed contacts of key 1, winding of relay 2, to battery. The other branch of the circuit extends over land line L to flying field F4, relay at F4 correspond- 75

ing to relay 79, land line L extending to terminal station #2, normally closed contacts of key 114, winding of relay 115, to battery. Relay 2, at terminal station #1, operates and closes its contacts 3, thereby closing an energizing circuit for the operating magnet 12 of the register CR and the slow-to-release relay 19. Relay 19 operates to start the tape 15 and the operating magnet 12 attracts its armature 13, thereby forcing pencil 14 into contact with tape 15 and recording the first dot of the field code.

It will be noted that the lower bank contacts 4, 6, 7, and 9 of the rotary switch CS are multiplied together and connected to the winding of relay 95. Thus it will be seen that as the switch rotates its wipers, a circuit is closed for relay 95 when wiper 93 moves into engagement with each of these four bank contacts. Each time relay 95 operates it sends another ground impulse to each of the two terminal stations and causes another dot signal to be recorded on the registers at these terminals in a manner already described. The field code for flying field F3 consists of one dot, pause, two dots, pause, one dot, as governed by the wiring of the lower bank contacts of the rotary switch. Ground impulses in accordance with this signal are transmitted to the two terminal stations and recorded on the registers such as CR. Each of the four intermediate flying fields has a different code signal. The attendants at the terminal stations are thereby notified at which particular flying field the plane is preparing to land.

Briefly summarizing what has occurred at each of the terminal stations, the attendant is first informed of the arrival of a plane at one of the intermediate flying fields by the sounding of the bell 154 and the lighting of one of the lamps, such as 1 or 11. One of these lamps is provided for each company operating planes over the route and the attendant immediately knows which company owns the plane which is preparing to land. The series of identifying impulses which causes the lighting of one of the lamps also operates the recorder CR which records a number of dots, which may be used to identify frequencies. The field code is then received and recorded on the register CR, directly after the identifying signal. A permanent record is thereby kept of the landing of all planes and the particular field at which they landed.

The rotary switch CS continues its rotary movement until the wipers 92 and 93 have been returned to their normal position. During the time that the field code was being transmitted by the rotary switch, relay 83 operated and opened contacts 84, thereby opening the initial energizing circuit of the rotary magnet 89 and relay 97. Thus the rotary switch is prevented from again operating when its wiper 92 is returned to normal and engages the normal bank contact. Relay 83, in operating, also closes its contacts 85, thereby completing an obvious circuit for the slow-to-release relay 87. Relay 87 operates and closes its contacts 88, but this has no particular effect at this time.

Everything is now in readiness for the pilot to land. The correct flood-light for landing, as determined by the wind direction, has been turned on. The light above the hangar owned by the company whose plane is approaching the field has also been lighted. The two terminal stations have been informed that a Company A plane is above flying field F3 and is preparing to land.

It will be assumed that the pilot has landed

his plane and has taxied to his hangar. Each hangar is provided with a release key, such as 76, Fig. 2, all of these keys being in multiple. When the pilot reaches his hangar he depresses key 76, thereby opening the locking circuit of relays 56, 56, 57 and 81. All of these relays release. Relay 56 opens its contacts 58, thereby opening a further point in the locking circuit of the relays, and closes its contacts 59, thereby again preparing its initial energizing circuit. Relay 60 opens its contacts 61, thereby opening the circuit of relay 108 and allowing it to release. Relay 108 opens one side of the power supply to the flood and hangar lights at contacts 107. Relay 60 also opens the contacts 62, thereby opening the 15 other side of the power supply to the light at hangar H1. All the lights at the flying field have now been extinguished.

Relay 81, in releasing, opens its contacts 82, thereby opening the energizing circuit for relay 83. Relay 83 releases and at contacts 84 again prepares the initial energizing circuit of the rotary magnet 89 of the switch CS. Relay 83 also opens the circuit of relay 87 at contacts 85 and closes a circuit for the rotary magnet 89 of the rotary switch at contacts 86. This circuit extends from ground, contacts 86, contacts 88, normal bank contact of the switch CS, wiper 92, rotary interrupter springs 91, winding of rotary magnet 89, winding of relay 97, to battery. Relay 87 is made slow to release and remains operated, after its circuit is opened at contacts 85, a sufficient length of time to allow the rotary magnet 89 and relay 97 to energize in the above-traced circuit. Relay 97 again opens its contacts 98, thereby opening the impulsive circuit controlled by relay 77 to prevent any identifying impulses from interfering with the transmitting of the field code should another plane approach the field and attempt to turn on the lights by the operation of its Vibroplex key. Rotary magnet 89 operates and interrupts its own initial energizing circuit by opening contacts 91. Upon releasing the magnet moves the wipers 92 and 93 into engagement with the second bank contacts. The magnet is again energized from ground at the second bank contact, wiper 92, interrupter springs 91, winding of rotary magnet 89, winding of relay 97, to battery. The field code, consisting of one dot, pause, two dots, pause, one dot, is then again transmitted to the terminal stations in the same manner as previously described. This field code is again recorded on the register CR and informs the attendant at the terminal station that the pilot of the plane has turned off the lights at the 55 field F3.

The system is also arranged so that the pilot of a plane may turn off the lights without landing. To do this he operates his Vibroplex key 43 so as to close contacts 151 and holds it in this position to transmit a long dash signal to the field receiving set. In response to this signal, plate relay P operates and remains operated for a short interval. The closing of contacts 50 again operates relay 77 which also remains operated for a short interval. The closing of contacts 78 again completes the circuit from ground, back contacts 98 of relay 97, contacts 78, winding of relay 79, land line L extending to F2, winding of the relay at F2 corresponding to relay 79, land line 70 L extending to F1, winding of the relay at F1 corresponding to relay 79, land line L extending to terminal station #1, normally closed contacts of the key 1, winding of relay 2, to battery. In this case the circuit is maintained closed for a 75

sufficient length of time to allow the slow-to-operate relay 18 to energize. Relay 19 operates and opens its contacts 80, thereby opening the locking circuit of relays 56, 60, 57 and 81, and bringing about the turning off of the lights and the sending of the field code as described above.

Should the attendant at either terminal station, having been notified that a plane belonging to Company A is over flying field F3, wish the pilot to continue and not land, he may turn off the lights at the flying field from the terminal station. To do this he depresses the key, such as 1 in Fig. 1, thereby closing a circuit from ground, key 1 in its operated position, land line L extending to F1, relay at F1 corresponding to relay 19 of F3, land line L extending to F2, relay at F2 corresponding to relay 19, land line L extending to F3, relay 19, land line L extending to F4, relay at F4 corresponding to relay 19, land line L extending to terminal station #2, normally closed contacts of key 114, winding of relay 115, to battery. Relay 19 operates in this circuit, and by opening its contacts 80, brings about the extinguishment of the lights and the sending of the field code as described above. The turning off of the lights in this manner is a signal for the pilot to continue to the next flying field and not land at field F3.

The pilot of a plane over the flying field F3 may also transmit messages over the land line L by means of telegraph signals. To do this, the pilot operates the Vibroplex key 43 so as to close contacts 151 in accordance with the dots and dashes of the telegraph message. These signals are received by the field radio receiving set RR which in turn operates plate relay P. Relay P will be operated a comparatively short time for the dots of the signal and a relatively long time for the dashes of the signal. Each time relay P operates, it closes an energizing circuit for the relay 11 at contacts 50. Relay 11 is thereby energized in accordance with the dots and dashes of the telegraph message. At contacts 18, a corresponding group of dot and dash impulses are transmitted over the land line L to each of the two terminal stations. The relay 2 at terminal station #1 and relay 114 at terminal station #2 respond to these impulses and in turn operate the registers, such as CR, to record the complete telegraph signal. The attendants at the stations may then take the telegraph message from the recording tapes.

The signals from the intermediate flying field to the terminal stations may be transmitted by radio instead of over the land line L. This is done by means of the field radio transmitter FT shown in Fig. 2. When the Vibroplex key 43 of an airplane approaching a field is set in vibration and the relay P responds to the resulting series of impulses, a circuit is closed for relay 51 each time relay P closes its contacts 50. As previously explained, one of the tuned relays, such as 53, is operated by the series of identifying impulses. This results in the operation of relays 56, 60, 57 and 81. Relay 57, upon operating, closes its contact 63, thereby completing the filament circuit of tube 75 of the field radio transmitter FT. The field transmitter is now in readiness to transmit the signals received by the relay 51 and repeated at its contacts 52. The radio transmitter FT may be any one of a number of well known makes and its detailed operation will not be explained. It will be seen from the fore-75 going that the radio transmission of the signals

may be used as an alternative of the transmission over the land line L.

The operation of the fog indicating system will now be explained. Each intermediate flying field is equipped with a photo-electric cell, such as PH shown within the dotted rectangle in Fig. 3. This cell is mounted at one side of the field and may be located about one hundred feet in the air. Directly across from the cell and at the same height is mounted a source of light within a parabolic mirror or reflector so as to project a very narrow beam of light directly into the telescopic end of the photo-electric cell. In addition, each flying field is equipped with an oscillator, such as shown at O. The oscillator at each field operates at a different frequency. In the case illustrated, the oscillator at flying field F1 is arranged to transmit a wave at 100 cycles, the oscillator at F2 is arranged to transmit at 200 cycles, the oscillator O at F3 is arranged to transmit at 300 cycles, and the oscillator at F4 is arranged to transmit at 400 cycles per second. In addition, each field is equipped with two tuned receivers arranged to receive the fog alarm signals from the two adjacent fields. Thus the flying field F3 is equipped with a receiver which responds to the 400 cycle alarm signal received from F4 and also with a receiver which responds to the 200 cycle fog alarm signal received from F2. Each terminal station is provided with a receiver and a recorder for each of the fog alarm frequencies.

The operation of the fog alarm system will now be explained in detail in connection with the apparatus shown at flying field F3 and terminal station #1. Normally, with the beam of light B from the light 116 directed into the photo-electric cell PH, current is allowed to flow through the photo-electric cell and resistance 146 from battery 147. The resistance 146 is of such a value that the voltage drop across the resistance with current flowing through the photo-electric cell maintains the grid of tube 117 at zero or at a positive potential with respect to the filament. This allows a plate current of sufficient value to flow in the plate circuit of tube 117 to operate relay 118 and maintain it operated as long as the beam of light B is shining into the photo-electric cell.

It will now be assumed that fog is present at flying field F3 and has cut off the beam of light B from the photo-electric cell PH. As soon as the light is cut off from the cell, current ceases to flow in the above described circuit including the photo-electric cell, resistance 146, and the battery 147. The voltage drop across resistance 146 drops to zero and the grid of tube 117 assumes a negative potential with respect to the filament. This negative bias on the grid of tube 117 reduces the plate current through relay 118 to a sufficiently low value to allow relay 118 to release. Contacts 119 close and complete the battery circuits for the oscillator O. The oscillator O is a tuned reed oscillator of the type disclosed in my co-pending application previously referred to and a detailed description of its operation need not be given here. It is thought sufficient to state that the tuned reed 122 is tuned to a frequency of 300 cycles per second and a current of this frequency is therefore caused to flow through winding 124 of the transformer located in the plate circuit of tube 123.

The current in the primary coil 124 induces a current of the same frequency in the secondary coil 125 of the transformer. An artificial line, comprising the variable resistance 126 and the

variable condenser 127, is provided so that none of this induced current passes through coil 128 of the receiving apparatus. A portion of the induced current passes through this artificial line 5 to ground and the remainder passes through condenser 130 to the land line L by way of conductor 104. The manner in which the induced current is received and identified at the flying fields F2 and F4 will be described later in connection with the receipt of a fog alarm signal 10 at flying field F3. A portion of this induced current is transmitted to terminal station #1 through condenser 42, over land line L extending to flying field F2, condenser 41, land line L extending to F4, condenser 40, land line L extending to terminal station #1, condenser 20, winding 21 of the transformer, to ground. A portion 15 of the current is also transmitted to terminal station #2 by way of land line L and condenser 148 to receiving equipment at terminal station #2 similar to that shown at terminal station #1.

Referring now to the receiving equipment at terminal station #1 shown in Fig. 1, the 300 cycle current flowing in the primary coil 21 of the 25 transformer induces a current of like frequency in the secondary coil 22. This induced current varies the potential on the grid of tube 23 and results in a 300 cycle plate current flowing through the tuned relays, such as 27 and 24. 30 Four such relays are provided, one for each of the frequencies used by the four intermediate flying fields. It will be assumed that relay 24 is arranged to respond to 300-cycle current, that is, the tuned reed 25 is adjusted to vibrate at 300 35 cycles per second. When the reed 25 is vibrating at a certain amplitude in response to the 300-cycle current through the relay 24, it opens contacts 26, thereby opening the circuit of the normally operated relay 30. Relay 30 releases and, 40 by closing its contacts 31, completes an obvious circuit for the operating magnet 33 of the register FR2 and the lamp 32 in multiple. Lamp 32, being lighted, immediately notifies the attendant at the terminal station that there is fog at flying field 45 F3. Magnet 33 attracts its armature and brings the pointer in contact with cylinder 34, thereby making a record of the fog condition at the flying field F3 and also of the time at which this condition prevailed.

The operation of the fog alarm receiving apparatus at field F3 will now be explained. It 50 will be assumed that fog is present at flying field F2 and that the oscillator at F2, corresponding to O at F3, is superimposing a 200-cycle current 55 on the land line L. This current is received at F3 through condenser 42, over conductor 104, condenser 130, right half of coil 125, primary coil 128 of the receiving transformer, to ground. The resulting voltage induced in the secondary coil 60 129 of the transformer varies the potential on the grid of tube 131 at this same frequency. This results in a 200-cycle plate current which passes through the tuned relays 132 and 133. The tuned reed 134 of relay 132 is adjusted to respond to a 65 current of 200 cycles which is the transmitting frequency of F2, while the tuned reed 136 of relay 133 is adjusted to respond to a current of 400 cycles which is the transmitting frequency of F4. Accordingly the 200 cycle plate current passing 70 through the relay 132 sets the tuned reed 134 into vibration. When the vibrations reach a certain amplitude, reed 134 opens contacts 135, thereby opening the energizing circuit for the normally operated relay 138 and allowing it to 75 release. The closing of contacts 139 completes a

circuit from one side of the power supply source, conductor 143, contacts 139, primary winding 144 of the transformer T1, to the other side of the power supply source by way of conductor 142. The alternating current passing through primary coil 144 of the step-up transformer T1 induces a relatively high voltage in the secondary coil 145. This results in the lighting of the neon lamp indicator N1. This neon lamp indicator is in the form of an arrow pointing in the direction of flying field F2, and, when lighted, informs any pilot flying over the field that there is fog at field F2. Similarly, the neon lamp indicator N2 is controlled by frequency relay 133. In this manner a pilot approaching any of the four intermediate flying fields is immediately notified if there is fog present at either of the two adjacent fields. The attendants at the terminal stations are also notified of the fog condition and a permanent record is made showing the time that such condition prevailed.

Having described the invention what is thought to be new and is desired to have protected by Letters Patent will be set forth in the appended claims.

What is claimed is:

1. In combination, an air route comprising two terminal stations and a number of intermediate flying fields connected by a land line, each of said fields having an identifying code signal, lights at 30 each field, airplanes having transmitters, means controlled by the transmitter of an airplane over one of said fields for turning on the lights at said field, means for transmitting the code signal of said field over said land line to inform said terminal stations that an airplane is attempting to turn on the lights at said field, means including said first means controlled from said airplane or from either of said terminal stations for turning off the lights at said field, said second means responsive to said last means for repeating the code signal over said land line to notify the terminal stations that said last means is being operated to turn off the lights at said field.

2. In combination, an air route comprising a 45 terminal station and a number of landing fields, each field having an identifying code signal, airplanes each having a transmitter for transmitting a distinctive signal, means at each field responsive to the transmitter of any airplane preparing to land at the field for transmitting a continuous signal to said terminal station to inform the station of the character of the plane, means responsive to said signal after a time interval for transmitting the code signal of the 50 field to notify the terminal station of the particular field at which said plane is preparing to land, and means for rendering said first means inoperative while said code signal is being transmitted.

3. In combination, a flying field having a plurality of floodlights and a plurality of hangar lights, a current source, a plurality of tuned relays each responsive to a different frequency, means in an airplane over said field for transmitting a series of impulses at a predetermined frequency to operate one of said relays, means common to all of said relays and controlled by any one of them for closing one side of said current source to all of said lights, means controlled 65 by wind direction for closing the other side of said current source to the proper floodlight, and means controlled by the operated relay for closing said other side of said current source to the proper hangar light as determined by the fre- 70 75

quency at which the impulses are transmitted from said airplane.

4. In a signaling system for airplane landing fields, a plurality of planes each having a transmitter for always transmitting a distinctive signal, a plurality of landing fields each having a receiving device and landing lights, said fields linked together by a land line, the receiving de-

vice at each field responsive to a signal transmitted from any one of said airplanes to light the lights at a landing field and to retransmit over the land line a signal indicative of the airplane from which the signal was received and the particular field at which it was received. 5
